UNITED STATES PATENT OFFICE

CHARLES C. BRIDWELL, OF WESTERVILLE, OHIO

TYPEWRITING MACHINE

Application filed February 18, 1927. Serial No. 169,167.

My invention relates to typewriting machines. It relates, more particularly, to a typewriting machine so constructed that its efficiency as a typewriter will be materially increased while, at the same time, being adapted to ledger posting, bill and statement writing or similar work, together with means for assisting in assembling the work sheets in operative position in the machine.

10 Heretofore, typewriting machines adapted for use as a billing and bookkeeping machine have been so constructed as to be inapplicable for ordinary typewriting work. Further, these machines have not been adapted for 15 billing, statement writing and ledger posting in the same operation. This has been due to the fact that ledger sheets are of a different size than those ordinarily used for billing and statements and no means has 20 been provided for maintaining various sized sheets in proper relation to each other while being assembled in the machine. Also, all sheets have, heretofore, been inserted in a typewriting machine with a sliding action, 25 which action has a tendency to disarrange the sheets with respect to their desired relative position to each other.

The means for assisting in assembling the work sheets in proper position in the machine is generally known as a collating device and has previously, in most instances, formed an integral part of the machine. Such an arrangement is bulky and, in many cases, undesirable, due to the space required and the time necessary to assemble a plurality of sheets and, in some instances, only sheets of the same size may be conveniently used. Billing or ledger posting on a typewriter, not equipped with a collating device, is also undesirable, due to the time expended in arranging the sheets in the typewriter, the difficulty in keeping a number of sheets in their proper position and the danger of crimping or otherwise distorting the sheets. Furthermore, typewriters that have been

equipped with collating devices have usually had their parts so arranged that it was undesirable or even impossible to use them for ordinary typewriting work.

One object of my invention is to provide a 50 collating device for typewriters that does not destroy any feature had by the typewriter prior to this change.

Another object of my invention is to provide a device that, when attached, increases 55 the advantages of the typewriter in that it will simultaneously complete several operations at the speed of an ordinary typewriter.

A further object of my invention is to provide a device wherein the papers are 60 placed in the typewriter in writing position and no further adjustment is necessary after the papers are once so placed.

A still further object of my invention is to provide a device wherein the sheets of 65 paper may be placed in the machine at any position desirable, with relation to one another, and held securely in that position while the platen of the typewriter is being lowered into operative relation to the papers.

A still further object of my invention is to provide a device that will facilitate removal of the papers from as well as their insertion into the typewriter without revolving the platen and which will thereby eliminate the danger of crimping or otherwise distorting the papers.

Other and further objects of my invention will appear from the following description and the preferred embodiment of my invention will be seen in the accompanying drawings wherein similar characters of reference designate corresponding parts and wherein:

Figure 1 is a perspective view showing a plurality of work sheets in writing position in a typewriter embodying the features of my invention prior to removal of the clamp.

Figure 2 is a perspective view showing the platen of the typewriter in raised posi-

tion to facilitate insertion into or removal of the papers.

Figure 3 is a perspective view of the opposite end of the typewriter shown in Figure 1 showing the changes necessary in the 5 construction of the typewriter.

Figure 4 is also a perspective view of the clamp-holding board on which the papers are arranged prior to their insertion into the 10 typewriter.

Figure 5 is a view similar to Figure 4 showing the papers clamped together ready for insertion into the typewriter.

Figure 6 is a perspective view of the clamp 15 shown in Figures 4 and 5.

With reference to Figures 1, 2 and 3 of the drawings, I have shown a platen 1 that may be swung into or out of operative relation to the work sheets assembled in a typewriter.

20 The platen 1 shown in these figures is particularly adapted to a "Royal" typewriter, although not limited thereto, since by minor variations in the constructions of the typewriter, such a platen may be adapted to use 25 on any type of typewriter. This platen 1 is mounted on a platen frame 2, which is pivoted to the main typewriter frame 3, as at 4. The swinging movement of the platen is governed by the slotted arm 5 having one 30 end rigidly attached to the platen frame 2, as at 6, and the opposite end slidably attached, by a slot and pin construction, to the main typewriter frame 3, as at 7.

Pivoted on the platen frame 2, 35 is the usual paper guide 8 which is adapted to keep the sheet or sheets of paper from interfering with the typewriter mechanism. The platen frame 2 also carries the usual line space lever 9 and the variable line spacer 40 10, on which the stop has been placed, as at 12', to permit the shaft 12 to enter the slot 11.

The main typewriter frame 3 is slotted, as at 11, to receive the shaft 12 on which the 45 platen is mounted. Adapted to hold the platen shaft 12 in the slot 11 and the platen 1 in operative relation on the sheet or sheets of paper, is the catch 13 actuated by the spring 14. This spring-actuated catch is 50 adapted to engage a lug 15 rigidly attached to the main typewriter frame 3. The movable platen frame 2 is provided with a rod 16 which acts as a brace and strengthens the movable platen frame.

55 Figures 4 and 5 show the board 17 which is adapted to hold the sheet or sheets of paper in proper position with relation to the spring clamp 20 prior to their being clamped together and inserted into the typewriter.

60 This board 17 is provided with the grooves 18 and grooved upright posts 19 to receive the spring clamp 20 and hold it in proper position. The board 17 is also equipped with the paper guides 25. The clamp 20 is, prefer- 65 ably, of the form shown in Figure 6 and

consists of a flat portion having a spring catch 21 and a flange 22 thereon and a flat spring portion 23 hinged thereto by the hinge 24.

It is preferable that two or more grooves 18 be provided in the board 17 so that, in adjusting the papers with relation to the spring clamp 20, held by one of the grooves, it will not be necessary to run the sheet or sheets off the board when the last entry on the sheet 70 or sheets is near the end of the sheet or sheets or, in other words, when an entry is made on the bottom of a sheet. This is plainly shown in Figure 4 of the drawings. This would also be true if there were only one groove in the board and an entry was to be made near the top of the sheet.

80 In operation, the spring clamp 20 is placed in one of the grooves 18 of the board 17 and various sized sheets of paper are then placed on the board 17, as shown in Figure 4. The papers are, preferably, marked with dotted lines or numbers along their edges to facilitate correct arrangement of the sheets. When the papers have been properly arranged, the 85 spring clamp 20 is closed, as shown in Figure 5, and the papers are ready for insertion into the typewriter. Bifurcated posts 26 have been provided on the main typewriter frame to receive the flange 22 of the spring 90 clamp 20 so that the papers will be held in proper position while the platen is being lowered. It is important that the grooves 18 and the guides 25 on the board 17 be absolutely true as regards proper relative position so that the papers, when placed in the 95 clamp and typewriter, will be in position for writing and no further adjustments of the papers will be necessary. After the papers have been placed in the typewriter and the 100 movable platen has been brought into operative relation to the papers, the clamp 20 may be removed by releasing the spring catch 21 and placed upon the board 17 ready to receive further paper.

105 It will be clearly obvious, by referring to the previous description, that I have provided a collating device for a typewriter that does not destroy any feature or take away any advantage had by the typewriter prior to this change. A typewriter, when equipped with my invention, will function identically the same as an ordinary typewriter, insofar as ordinary typewriting work 110 is concerned, and will have an added advantage in that it will complete simultaneously several operations at the speed of an ordinary typewriter.

115 It will also be clearly obvious, by reference to the previous description, and the 120 drawings attached hereto, that I have provided a device wherein sheets of paper of various sizes may be placed in the typewriter in any position, with relation to one another, 125 that is desired and that the papers may be 130

so adjusted on the collating board that they will be in writing position, when clamped together and placed in the typewriter, requiring no adjustment after being placed in the typewriter.

5 Furthermore, it will be obvious that, by using a movable platen that may be moved into or out of operative relation with the work sheets in a typewriter, I have provided
 10 a device facilitating the removal of the papers from as well as their insertion into the typewriter. Such a device will also eliminate much of the danger of crimping or otherwise distorting the paper in the type-
 15 writer.

Having thus described my invention, what I claim is:

1. In a typewriting machine, a movable carriage, a platen frame carrying a rotatable platen, said frame having supporting means pivotally mounted on said carriage at a point remote from the normal operating position of the platen to permit the platen to be moved to a position such as to uncover 25 the space normally occupied by the platen when in operative relation.

2. In a typewriting machine, a movable carriage, a platen frame carrying a rotatable platen mounted upon pivots at the rear 30 of said carriage, the mounting of said platen permitting the platen to be moved to a position such as to uncover the space normally occupied by the platen when in operative relation thereby enabling a work sheet to be 35 positioned in said space.

3. In a typewriting machine, a movable carriage, a platen frame carrying a rotatable platen mounted upon pivots at the rear of said carriage, the mounting of said platen 40 permitting the platen to be moved to a position such as to uncover the space normally occupied by the platen when in operative relation thereby enabling a horizontally disposed work sheet to be moved vertically into 45 position in said space.

4. In a typewriting machine, a movable carriage, a platen frame carrying a rotatable platen mounted upon pivots at the rear of said carriage, the mounting of said platen 50 permitting the platen to be moved through an arcuate path to a position such as to uncover the space normally occupied by the platen when in operative relation thereby enabling a work sheet to be positioned in 55 said space.

5. In a typewriting machine, a movable carriage, a platen frame carrying a rotatable platen pivotally mounted at the rear of said carriage, the mounting of said platen 60 permitting the platen to be moved to a position such as to uncover the space normally occupied by the platen when in operative position, removable means for holding the work sheet in position while said platen is 65 being moved into operative relation with

said work sheet, and means for maintaining said removable sheet holding means in such position with respect to said platen that further adjustment of the work sheet prior to writing after the platen has been moved 70 into operative relation therewith is unnecessary, said maintaining means embodying supporting means mounted on said machine and spaced from said platen.

In testimony whereof I hereby affix my 75 signature.

CHARLES C. BRIDWELL.
